UNITED STATES PATENT OFFICE.

WILLIAM M. UNDERHILL, FRANCES M. UNDERHILL, AND CLARA M. UNDERHILL, OF GREENWICH, CONNECTICUT.

DESIGN FOR A TOY.

46,858.

Specification for Design.

Patented Jan. 12, 1915.

Application filed October 31, 1914. Serial No. 869,709. Term of patent 7 years.

To all whom it may concern:

Be it known that we, WILLIAM M. UNDERHILL, FRANCES M. UNDERHILL, and CLARA M. UNDERHILL, citizens of the United States, residing at Greenwich, in the county of Fairfield and State of Connecticut, have invented a new, original, and ornamental Design for Toys, of which the following is a specification, reference being had to the accompanying drawing forming part thereof.

The figure is a perspective view of the toy, showing our new design.

We claim:

The ornamental design for a toy, as shown.

WILLIAM M. UNDERHILL.
FRANCES M. UNDERHILL.
CLARA M. UNDERHILL.

Witnesses:

A. W. W. MARSHALL,
ROBERT TAYLOR.
